UNITED STATES PATENT OFFICE.

WILLIAM A. RADFORD, OF CHICAGO, ILLINOIS.

BOOK.

1,371,439.

Specification of Letters Patent. Patented Mar. 15, 1921.

Application filed August 18, 1920. Serial No. 404,461.

To all whom it may concern:

Be it known that I, WILLIAM A. RADFORD, a citizen of the United States, residing at Chicago, in the county of Cook and State of Illinois, have invented a certain new and useful Improvement in Books, of which the following is a full, concise, clear, and exact description, reference being had to the accompanying drawings, forming a part of this specification.

My invention relates to books and has specific reference to a particular arrangement of book designed to function primarily as an advertising medium.

The fundamental object in devising the present arrangement of book is to provide an advertising medium which will have the highest possible degree of permanency; that is to say, one which will insure its continued existence and utility as an advertising medium after the practical utility of the device is at an end. In the preferred embodiment of the invention, this advertising medium comprises a calender consisting of the usual separate month sheets or pages having associated therewith any desired advertising matter. The calendar as an advertising medium fulfills a practical utility, but as heretofore arranged, the advertising utility of each month sheet or page is short lived owing to the fact that upon serving its purpose, each sheet or page is generally removed and thrown away. The advertising utility of the calendar therefore diminishes with the removal of each month sheet and the advertising utility of the calendar as an entirety generally ceases to exist after the expiration of the calendar. I attain a greater degree of permanency of the advertising medium by combining a unique arrangement of serial poster with the month sheets of the calendar, whereby there is induced a desire to retain each separate month sheet upon its removal from the calendar for the purpose of completing the serial poster. This serial poster preferably consists of a highly colored pictorial illustration, such as a rural panorama, which is cut into sheets dividing the panorama into contiguous sections. These several sheets are bound one upon the other in the form of a book, and upon each page is printed a calendar table of the days of a month. The pictorial representations on each page of the book are incomplete with respect to the entire illustration, but each one has a complete object or point of individual

interest depicted thereupon. The individual illustrations end abruptly at the margins of the page so that there is induced the desire to post up each successive page in 60 contiguous arrangement in order to complete the entire poster and appreciate its composite attractive appearance. It will thus be seen that as each successive calendar page of the book serves its purpose as a calendar 65 sheet, it is removed from the book and added to the preceding sheets which have already been posted up and thus the complete panorama or other picture is gradually produced. In this manner the value of the advertising 70 matter associated with the various sheets of the book does not terminate with the removal of the particular sheet with which it is associated, but continues during the formation of the panorama, as well as during 75 the life of the same upon completion. The successive pages of the serial poster may also embody printed matter of particular interest to the intended patronage; this printed matter may be supplementary to the pictorial illustrations. It may also be arranged on the sheets so that it is gradually completed for reading by the successive posting of the several sheets in a particular arrangement. The provision of the calendar table on each 80 page of the book lends a practical utility to each page thereof, tends to direct attention to the advertising value of the device by extending the completion of the poster over a long period of time as a result of 85 the successive additions thereto at the end of each month. It is to be understood, however, that the invention is not limited to the use of a calendar in conjunction with the serial poster, as other forms of printed matter or devices of utilitarian or esthetic character may be substituted therefor.

One particular field of advertising in which the present arrangement of book is peculiarly advantageous is among farmers 100 and suburbanites. The decorative utility of the serial poster as a form of decoration for the interior walls of a barn, shed or the like will immediately appeal to the farmer and induce him to post up the successive 105 month pages of the book until the panorama is completed. In the accompanying drawing in which I have illustrated a particular embodiment of my invention I have illustrated the serial poster as depicting a rural 110 panorama specifically intended for this field of advertising.

Referring to the drawing:

Figure 1 is a perspective view of an advertising book embodying the teachings of my invention; and

- 5 Fig. 2 is a fragmentary elevational view showing how the poster sheets are arranged as they are removed from the advertising book to gradually complete the panorama.
- 10 The book comprises a plurality of sheets or pages bound together along their upper edges by means of a metallic binding strip 6. The binding strip 6 comprises a relatively thin metallic sheet, one edge of which 15 is positioned along the coinciding upper edges of the sheets 5 at a slight distance therefrom. The upper edges of the sheets 5 are then bent back over the upper edge of the strip 6 whereupon the strip 6 is bent up 20 and over the entire upper edge of the sheets 5 as shown forming a bead therealong. A suitable hanger 7 secured in place by the binding strip 6 is provided for attaching the book or calendar to a wall or other supporting surface.

25 Each of the pages 5 is provided with a table 8 of the days of a month. The pages are arranged so that the months will be in successive order, that is, upon the expiration 30 of the first month January, and the removal of the first page of the calendar the second page having the month of February thereon, will be disclosed.

35 Advertising matter associated with each of the tables 8 goes hand in hand in the particular embodiment shown with the associated illustrations in the advertising scheme of the calendar. For example this advertising matter which may be in the 40 nature of daily reminders 9 spacing or separating the numerals indicating the days of the month vertically, to which arrangement my co-pending application, Serial No. 404, 452 filed Aug. 18, 1920, is directed, or it may 45 be otherwise associated with the table 8. This advertising matter sets out, for example, on the first page, the conveniences and advantages of a modern home for the construction of which the distributor of the 50 calendar provides plans, materials, etc. The illustration on this page shows an attractive home 10. On the next page, designated 55 11 in Fig. 2 the advertising matter associated with the table 8 is directed to barns for the construction of which the distributor provides plans, materials, etc. The illustration in connection with this page shows a barn 12. Continuing to the next 60 page designated 13 in Fig. 2, the advertising matter associated with the table 8 thereof, is directed to the provision of a modern hog-house for the construction of which the distributor provides the plans, materials, etc. The illustration associated with this 65 page 13 shows a hog-house 14. The pages

have a natural background or setting such as will give a realistic appearance to the view and the objects all have a congruous relation to each other in a panoramic group scene.

70 The illustrations on the successive pages of the book, which illustrations may be variously colored, are supplementary and so arranged that they may be joined as shown in Fig. 2 as the months expire and the pages are removed gradually adding to the panorama until finally a complete and entire view is had. For example, in distributing such a book to an agriculturalist, the first page may upon removal from the book be 75 attached to the interior of a barn, shed or the like, which interiors are frequently covered with most any available posters. Then upon removal of the second page from the book, it may be positioned immediately to 80 the right of the first page and secured in place and so on.

85 It will now be apparent that the utility of the device of my invention is three-fold: First, the days of the months are indicated 90 in successive order; second, an attractive and highly effective advertising arrangement is had; and third, an attractive panorama poster is had after the various sheets of the calendar have served to indicate the 95 days, weeks and months in proper order. Such a poster in addition to its attractiveness is, as hereinbefore pointed out, quite useful, and in this manner the advertising value of a calendar instead of ceasing with 100 the removal of the various indicating sheets from the calendar continues during the formation of the attractive as well as useful panorama, as well as during the life of the same upon completion.

105 It will be apparent as hereinbefore set out that a number of modifications and different arrangements may be had, all of which secure the advantages of my invention, the particular embodiment which I have illustrated and described, being only one form in which the invention may appear. I have therefore drawn the appended claims accordingly.

110 I claim:

115 1. In a device of the class described, the combination of a book comprising a plurality of pages bearing matter forming contiguous sections of a continuous panoramic pictorial representation of a scene having 120 a natural setting, said pages being bound one upon another along an edge of the sections which edge does not intersect the pictorial representation and being adapted upon detachment from said book to be 125 placed in contiguous arrangement upon a common backing for forming said pictorial representation.

2. In a device of the class described, the combination of a book comprising a plu- 130

rality of pages bound one upon another said pages bearing matter consisting of substantive sections forming contiguous sections of a pictorial representation, each page having 5 a complete object or scene of individual interest supplemental printed matter associated with each of said pages suggesting the periodical removal of each of said pages, said pages being adapted upon removal 10 from said book to be placed in contiguous alinement upon a suitable backing for forming said pictorial representation.

3. In a device of the class described, the combination of a book comprising a plurality of pages bound along the top, said pages bearing matter forming contiguous sections of a pictorial illustration depicting a panorama or the like, said pages bearing each a complete object or scene of individual 15 interest, a calendar associated individually with each of said pages, said pages being 20

adapted upon removal from said book to be posted in contiguous alinement for forming said pictorial illustration, in stages corresponding to the removal of the calendar 25 pages.

4. In a book a series of pages bearing each a complete pictorial representation of an object, said objects represented on said pages being different but having a congruous relation to each other in a panoramic group scene said pages having each one edge which intersects the panoramic scene said pages being bound together along another edge, said pages bearing advertising matter 30 and bearing symbols suggesting the successive removal of the pages and the arrangement of the same adjacent each other to form said panoramic scene.

In witness whereof I hereunto subscribe 40 my name this 16th day of August, 1920.

WILLIAM A. RADFORD
